CLAIM

The ornamental design for a brush, as shown and described.

DESCRIPTION

FIG. 1 is a front, top and right side perspective view of a brush of my new design;
 FIG. 2 is a left side elevational view thereof;
 FIG. 3 is a top plan view thereof;
 FIG. 4 is a right side elevational view thereof;
 FIG. 5 is a bottom plan view thereof;
 FIG. 6 is a front elevational view thereof;
 FIG. 7 is a rear elevational view thereof, and,
 FIG. 8 is a rear, bottom and left side perspective view thereof.

(Continued)

The broken lines in the drawings depict portions of the brush
that form no part of the claimed design.
